UNITED STATES PATENT OFFICE.

AMBROSE S. VOSE, OF BROOKLINE, MASSACHUSETTS.

ADJUSTABLE HANDLE-BAR FOR BICYCLES.

SPECIFICATION forming part of Letters Patent No. 619,452, dated February 14, 1899.

Application filed November 22, 1897. Serial No. 659,373. (No model.)

To all whom it may concern:

Be it known that I, AMBROSE S. VOSE, residing in Brookline, in the county of Norfolk and State of Massachusetts, have invented an Improvement in Adjustable Handle-Bars for Bicycles, of which the following description, in connection with the accompanying drawings, is a specification, like letters on the drawings representing like parts.

This invention relates to bicycles and like vehicles provided with a handle-bar, and has for its object to provide a simple and efficient device or attachment by which the handles of said bar may be raised and lowered in a substantially short time while the machine is in motion, so as to adjust the said handles to any height desired by the rider, and whereby the said handle-bar is automatically locked in its adjusted position by the same mechanism. These and other features of this invention will be pointed out in the claims at the end of this specification.

Figure 1 is a vertical section and elevation of a sufficient portion of a bicycle handle-bar embodying this invention to enable it to be understood, the section being taken on the line 1 1, Fig. 2; and Fig. 2, a section on the line 2 2, Fig. 1, looking toward the left.

In accordance with this invention the handle-bar *a*, which may be of any suitable or usual construction and provided at its ends with suitable handles, (not shown,) has fast on it a worm-gear *a'*, preferably cut on a sleeve *a*², which is brazed or otherwise rendered fast on the said handle-bar.

The handle-bar and its attached worm-sleeve *a*² are adapted to turn in a cylinder *b*, formed in an enlargement or head *b'*, attached to or forming part of the steering-post *b*² or other support for the handle-bar. The head *b'* is provided on one side with a cylindrical opening *b*³, into which is extended a hollow plug or sleeve *b*⁴, provided with a worm *b*⁵ to engage the worm-gear *a'*. The front portion of the hollow plug or sleeve *b*⁴, on which the worm *b*⁵ is cut, is preferably made tapering, as shown in Fig. 1, while its rear portion is made cylindrical to fit closely into the opening *b*³. The worm-sleeve *b*⁴ is adapted to turn freely on a rod *b*¹⁰, provided with a head *b*¹² and at its front end with a screw-threaded portion *b*¹³, of reduced diameter, to form a

shoulder *b*¹⁵, against which a nut *b*¹⁶ is designed to abut and to engage the front end of the worm-sleeve, the said nut and head *b*¹² on the rod serving to prevent longitudinal movement of the worm-sleeve *b*⁴ on the rod *b*¹⁰. The threaded end *b*¹³ of the rod *b*¹⁰ engages a screw-threaded opening *b*²⁰ in the opposite side of the head *b'* and is locked by a screw *b*²¹, engaging a threaded socket in the end of said rod. The worm-sleeve *b*⁴ is preferably provided with a thumb-nut or wheel *b*³⁰, by which the worm may be easily turned to rotate the worm-gear, and thereby raise and lower the handles of the handle-bar into the desired position.

By making the worm *b*⁵ tapering, as described, wear may be taken up, so that said worm and worm-gear may be kept in close engagement, thereby maintaining the worm-gear sensitive to the rotation of the thumb-nut.

By means of the worm and worm-gear the handle-bar may be turned any desired amount, so that nice adjustment of the handles of said bar may be effected, and the said handle is locked in its adjusted position by the engagement of the worm and worm-gear. The cylinder *b* may, and preferably will, be closed at its ends by caps *c*, which may be screwed upon the ends of said cylinder, as shown in Fig. 2.

In practice the adjusting-nut *b*³⁰ is located on the side of the steering-post which faces the rider, so that the latter may adjust the handle-bar without dismounting from the machine and while the latter is in motion.

I claim—

1. In a cycle, the combination of the following instrumentalities, viz: the steering-post provided with a head having an opening, a handle-bar extended through said opening and provided with a worm-gear supported to rotate in said opening, a worm-sleeve provided with a thumb-nut or wheel and extended into said head to engage said worm-gear, a rod on which said worm-sleeve is loosely mounted, means to secure said worm-sleeve on said rod against longitudinal movement, and means to secure said rod in said head, substantially as described.

2. In a cycle, the combination of the following instrumentalities, viz: the steering-

post provided with a head having a cylinder b , the handle-bar a provided with the worm-gear a' within said cylinder, the rod b^{10} extended into an opening in said head substantially at right angles to the cylinder b and provided with a head b^{12} and at its front end with a screw-threaded portion b^{13} of reduced diameter, a tapering worm-sleeve b^4 loosely mounted on the rod b^{10} and engaging the worm-gear a' , a nut b^{16} to secure said worm-sleeve on the rod b^{10} against longitudinal movement, and means to secure the rod b^{10} to

said head, the worm-sleeve being provided with means whereby it can be turned to adjust the handle-bars while the machine is in motion and without dismounting therefrom, substantially as described.

In testimony whereof I have signed my name to this specification in the presence of two subscribing witnesses.

AMBROSE S. VOSE.
